(57) **CLAIM**

The ornamental design for a fragrance bottle, substantially as shown and described.

DESCRIPTION

FIG. 1 is a top, front, right side perspective view of a first embodiment of a fragrance bottle showing our new design;

FIG. 2 is a front elevation view thereof, the rear elevation view being identical thereto;

FIG. 3 is a side elevation view thereof, the opposite side elevation view being identical thereto;

FIG. 4 is a top plan view thereof;

FIG. 5 is a bottom plan view thereof;

FIG. 6 is a top, front, right side, perspective view of a second embodiment of a fragrance bottle showing our new design;

FIG. 7 is a front elevation view thereof, the rear elevation view being identical thereto;

FIG. 8 is a side elevation view thereof, the opposite side elevation view being identical thereto;

FIG. 9 is a top plan view thereof;

FIG. 10 is a bottom plan view thereof;

FIG. 11 is a top, front, right side, perspective view of a third embodiment of a fragrance bottle showing our new design;

FIG. 12 is a front elevation view thereof, the rear elevation view being identical thereto;

FIG. 13 is a side elevation view thereof, the opposite side elevation view being identical thereto;

FIG. 14 is a top plan view thereof; and,

FIG. 15 is a bottom plan view thereof.
